UNITED STATES PATENT OFFICE.

CHARLES L. BASTIAN, CHICAGO, ILLINOIS.

DISPENSING APPARATUS.

1,399,373.

Specification of Letters Patent.

Patented Dec. 6, 1921.

Application filed May 13, 1921. Serial No. 469,338.

To all whom it may concern:

Be it known that I, CHARLES L. BASTIAN, a citizen of the United States, residing at Chicago, in the county of Cook and State 5 of Illinois, have invented certain new and useful Improvements in Dispensing Apparatus, of which the following is a specification.

The invention relates to dispensing apparatus and is primarily adapted for dispensing carbonated beverages such as root beer where the mixture is made in the glass 10 upon a customer's order.

The object of the invention is, generally, to provide an apparatus of simple construction 15 and efficient operation, which will maintain the syrup in a sanitary condition and at a suitable temperature, and which will also cool the carbonated water to a temperature suitable for dispensing and drink- 20 ing.

A particular object of the invention is to maintain a substantially constant gravity pressure on the syrup at the draft arm to insure at all times an even, regular and 25 uniform flow whereby the operator may, by given manipulation of the draft arm, always draw off the same charge of syrup regardless of the level of the syrup in the supply tank.

Another important object is to provide a closed syrup jar for storing the syrup in the apparatus and having a valve which can be removed for filling the jar and which will be automatically opened when the jar 35 is arranged in its proper position so that the jar can be refilled and replaced under sanitary conditions and without spilling the syrup.

Another important object is to maintain 40 a constant charging supply of syrup from the syrup jar and provide for drawing off therefrom on a given operation of the draft arm not more than a predetermined quantity of syrup which should be sufficient as a 45 charge for one glass of the beverage, whereby uniformity in the quantity of the charge may constantly be maintained.

And a further object of the invention is to operate the charging means and dispense 50 the charge of syrup by a simple and ordinary manipulation of the draft arm lever, and to arrange the parts so that this lever may be operated to discharge a stream of

water into the glass without causing a discharge of syrup.

I have illustrated the invention in an apparatus designed primarily for dispensing root beer as a selected embodiment of the invention and referring thereto—

Figure 1 is a sectional elevation of the 60 invention.

Fig. 2 is a horizontal, sectional view on the line 2—2 of Fig. 1.

Fig. 3 is a detail sectional view showing a slightly different construction.

Referring to the drawings, 4 designates a cooling tank which may be inclosed in a barrel or keg 6 or some other display form. The cooling tank is spaced from the walls of the barrel and this space is 70 filled with some suitable packing material 6 to exclude heat. The carbonated water enters the tank from a suitable supply through the pipe 7 and passes through the cooler 8 and the pipe 9 to the draft arm 10. 75 The cooling tank is partly filled with ice 11 and a removable, insulated cover 12 forms a closure for the cooling tank and the barrel. A drain cock 13 is provided at the bottom of the tank and barrel.

The syrup jar 14 is removably supported on one or more brackets 15 within the tank. This syrup jar is smaller in diameter than the tank so that the supply of ice can be replenished without removing the jar. The 85 syrup valve is secured in the bottom of the jar at one end thereof and the jar may be provided with a well 16, Fig. 3, if desired, in which case the valve will be located in the bottom of the well. This valve com-

prises a body 17 which has threaded engagement with an opening 17' in the bottom of the jar and is provided with a central passage 18 and one or more lateral connecting passages 19. A valve stem 20 extends entirely through the valve body and carries the valve disk 21 on its upper end within the syrup jar to seat against the upper end of the central passage 18 for closing the syrup outlet. A spring 22 is 100 arranged on the other end of the stem between the valve body and a head 23 on the outer extremity of the stem. Beneath the syrup jar there is a charging tank 24 which is open at the top and is connected at the 105 bottom by pipe 25 with the syrup passage

of the draft arm. This draft arm can be made in any form suitable for the purpose and I have not considered it necessary to illustrate the construction of the draft arm and need only say that it is preferably of a form which will discharge syrup, a large water stream and a fine water stream.

When the syrup jar is in place in the tank the head 23 on the valve stem engages the bottom of the charging tank 24 and the parts are dimensioned and proportioned so that in this position the valve will be unseated to permit syrup to flow through the passages 18 and 19 into the charging tank. The syrup jar 14 is closed except by the valve and the charging tank is open at the top so that when the valve is opened syrup will flow by gravity into the charging tank until the lateral passages 19 are submerged and, since the valve remains open constantly while the syrup jar is supported within the cooling tank 4, a substantially constant level of syrup may be maintained in the charging tank 24, the supply in this charging tank being replenished automatically as a charge of syrup is drawn off through the draft arm. The level of syrup in the charging tank may be observed at all times through the gage 27 connected with the draft arm outside of the barrel. When the syrup jar is removed from the cooling tank for refilling or for any other purpose the valve will close automatically and immediately after the stem head is lifted from engagement with the bottom of the charging tank. The syrup jar may be refilled through the opening 17 after unscrewing and removing the valve, and after the syrup jar is refilled, the valve is screwed back into place in the opening 17' to form a complete closure for the jar so that it can be handled and replaced without spilling or leaking.

To insure a constant uniformity in the quantity of the syrup charge I provide a measuring cup 28 in the charging tank 24 which is normally located below the level of the syrup therein. This measuring cup is provided in its bottom with a discharge pipe 29 which telescopes and slides in a pipe 30 secured in the bottom of the charging tank and communicating with the pipe 25. The cup has upwardly projecting arms 31 in which a transverse pin 32 is secured and a link 33 is connected to said pin and to the outer end of a lever arm 34 which is secured on a rock shaft 35 mounted in the walls of the charging tank. A pinion 36 is rigidly mounted on this rock shaft 35 outside of the charging tank and is engaged with a toothed segment 37 on a lever 38 which is pivoted at 38' on the side of the charging tank. The other end of the lever 38 is pivotally connected by a connecting rod with the handle lever 40. This connecting rod comprises the end sections 41, 41' and the intermediate section 41". The section 41 is pivotally connected at its ends to the lever 38 and to the section 41". The section 41' is pivotally connected at its ends to the handle lever 40 and to the section 41". The section 41" is arranged to slide in a guide sleeve 42 which is secured in the walls of the barrel or keg and cooling tank. This sectional pivoted connecting rod permits the end sections 41 and 41" to swing with the segment lever 38 and handle lever 40 while the intermediate section 42 slides in a straight line.

The construction is such that normally the measuring cup is submerged in the charging tank while the handle lever is in closed position. When the handle lever is pulled forward, to the left in Fig. 1, the segment lever 38 is swung on its pivot to cause the segment by engagement with the pinion to rock shaft 35 and swing the arm 34 to lift the measuring cup until its top clears the level of the syrup. At or about the time the syrup discharge is thrown open by manipulation of the handle lever the measuring cup is lifted above the level of the syrup in the charging tank so that the charge of syrup, including that in the pipes as well as that in the cup itself, will flow freely and quickly through the handle lever into the glass. No more than this charge will flow even though the handle lever is held to open position of the syrup discharge for a longer period than is necessary to deliver the charge because the syrup must flow through the measuring cup from the charging chamber and while the handle lever is in position to hold the syrup discharge open the measuring cup will be above the level of the syrup in the charging tank. When the handle lever is returned to neutral, closed position, as shown in Fig. 1, the segment is out of operating engagement with the pinion so that the handle lever may be pushed backward, to the right in Fig. 1 to open the fine stream delivery without causing further movement of the pinion, the measuring cup or other connections.

It is highly desirable that a syrup charge of the same quantity should be delivered not only from one apparatus but from other apparatuses dispensing the same beverage so that uniformity of the product which is desired by the manufacturer will always be maintained. The manufacturer who puts a popular beverage on the market generally prepares his syrup with the intention that a predetermined charge will always be used in a glass of a certain size and the popularity of the beverage and the success of the manufacturer is to a considerable extent due to the manner in which the beverage is dispensed, and the public is entitled to the same uniformity in beverages which are dispensed in this way as it expects in bottled beverages. My present invention provides a sure and certain means for dispensing at all times a

uniform syrup charge of constant quantity and if a glass is used for which the charge is intended and the proper quantity of water is drawn the beverage should be disposed 5 as uniformly as if it were bottled by the manufacturer.

The syrup is maintained in a sanitary condition and is dispensed in an even, steady flow to the glass. The invention provides 10 for filling the syrup jar under sanitary conditions and for keeping the jar closed until it is replaced in position in the cooling tank. The syrup valve is always open while the syrup jar is in proper position in the 15 cooling tank and therefore the charging tank may be constantly filled with syrup to a pre-determined level sufficient at all times to supply an even, regular flow through the draft arm. The syrup will not spurt into 20 the glass but will flow in a steady, even stream and the measuring cup insures a uniformity of the syrup charge.

My invention is shown embodied in a simple form in an apparatus for dispensing 25 root beer and similar beverages but I do not intend to limit myself to this particular embodiment or use and I reserve the right to make any changes in the form, construction and arrangement of parts as fairly fall within 30 the scope of the following claims:

I claim:

1. A dispensing apparatus comprising a charging tank, means for maintaining a pre-determined level of syrup in said tank, a 35 draft arm having a handle lever, a measuring cup in the charging tank connected with said draft arm, and means connecting said handle lever with the cup whereby the cup may be raised to clear the level of the syrup 40 in the charging tank when the handle lever is moved to open the syrup passage in the draft arm and thereby permit the flow of a measured charge of syrup from the charging tank through the draft arm.
2. A dispensing apparatus comprising a 45 charging tank, means for maintaining a pre-determined level of syrup in said tank, a draft arm having a handle lever, a vertically movable measuring cup normally submerged 50 in the syrup in the charging tank and connected with the draft arm, and means connecting said handle lever with the cup whereby the cup may be raised to clear the level of the syrup in the charging tank when the 55 handle lever is moved to open the syrup pas-

sage in the draft arm and thereby permit the flow of a measured charge of syrup from the charging tank through the draft arm.

3. A dispensing apparatus comprising a charging tank, means for maintaining a pre-determined level of syrup in said tank, a draft arm having a handle lever, a pipe in 60 said charging tank connected with said draft arm, a vertically movable measuring cup normally submerged in the syrup in the 65 charging tank, a discharge pipe for said measuring cup telescopingly engaged with said charging tank pipe, and means connecting the handle lever with the cup whereby the cup may be raised to clear the level of 70 the syrup in the charging tank when the handle lever is moved to open the syrup passage in the draft arm and thereby permit the flow of a measured charge of syrup from the charging tank through the draft arm. 75

4. A dispensing apparatus comprising a charging tank, means for maintaining a pre-determined level of syrup in said tank, a draft arm having a handle lever connected with said draft arm, a rock shaft mounted 80 on the charging tank, and an arm carried by said rock shaft and connected with said measuring cup and actuated by the handle lever for operating said rock shaft to raise and lower the measuring cup. 85

5. A dispensing apparatus comprising a cooling tank, a charging tank supported in the cooling tank, means for maintaining a predetermined level of syrup in the charging tank, a draft arm supported on the cooling 90 tank and having a handle lever, a measuring cup in the charging tank connected with said draft arm, a guide in said cooling tank and means connecting the handle lever with the cup for raising and lowering the cup. 95

6. A dispensing apparatus comprising a cooling tank, a charging tank, means for maintaining a predetermined level of syrup in the charging tank, a draft arm mounted on the cooling tank and having a handle 100 lever, a vertically movable measuring cup in the charging tank connected with said draft arm, a guide in the cooling tank, a rod composed of pivoted sections slidably arranged in said guide and connected at one 105 end to said handle lever, and means connecting the other end of said rod with said cup.

CHARLES L. BASTIAN.
